UNITED STATES PATENT OFFICE.

HARRY T. LOOMIS, OF NEW YORK, N. Y.

DESIGN FOR WOVEN TEXTILE FABRIC.

41,813.

Specification for Design.

Patented Sept. 26, 1911.

Application filed October 10, 1910. Serial No. 586,405. Term of patent 8½ years.

To all whom it may concern:

Be it known that I, HARRY T. LOOMIS, a citizen of the United States, and residing at New York, in the county of New York and State of New York, have invented a certain new, original, and ornamental Design for Woven Textile Fabrics, of which the following is a specification, reference being had to the accompanying drawing, forming part thereof.

The figure is a plan view of a portion of a woven textile fabric showing my new design.

I claim:—

The ornamental design for a woven textile fabric as shown.

HARRY T. LOOMIS.
